UNITED STATES PATENT OFFICE

CLAUDE NAGLE, OF ELMIRA, NEW YORK, ASSIGNOR TO HARTFORD-EMPIRE COMPANY,
OF HARTFORD, CONNECTICUT, A CORPORATION OF DELAWARE

WINDSHIELD FOR LEERS

Application filed March 28, 1928. Serial No. 265,297.

My invention relates to glass annealing leers of the tunnel type in which controlled heat conditions are maintained first to bring the glassware to the proper annealing temperature and then to reduce that temperature gradually at a suitable rate to prevent strains from being set up in the glass articles.

It has been found that the maintenance of the proper temperature in this type of leer is often interfered with by the entering of cold air currents at either end of the leer. Such external drafts are more detrimental when they enter the hot or receiving end of the leer rather than the cool end. This is because it is in the earlier stages of annealing that the ware is most sensitive to temperature variations, and therefore the air entering the cool end of the leer must pass through nearly the full length of the heated tunnel before it blows on the ware in its critical stage of annealing, while drafts entering the hot end of the leer reach the ware very promptly with very little intermediate heating.

An object of the invention is to prevent such cold air currents from entering the leer, specifically by the provision of means for creating an air shield across the end of the leer. The statements made above as to the sensitiveness of the ware in the early stages of annealing to external drafts also apply to means for controlling air currents at the receiving end, unless such means are adjusted with a high degree of accuracy. The means employed by the present invention to prevent indrafts of air at the receiving end of the leer not only controls such drafts at the place where they are most detrimental, but does it without introducing irregularities of control which would, in themselves, be more or less detrimental.

This air shield not only prevents disturbance of the heat conditions in the leer, but also serves to increase the comfort of the persons who serve the leer when it is loaded by hand, by maintaining a cool environment at the receiving end at which ware is introduced into the leer.

These and other objects of the invention

will more fully appear in the following description, taken in connection with the accompanying drawings, in which:

Fig. 1 is a sectional elevation of the receiving end of a tunnel leer showing one embodiment of the invention applied thereto, 55

Fig. 2 is a perspective view of the upper part of the apparatus as shown in Fig. 1, 60

Fig. 3 is a modification of the means for holding the apparatus in place, particularly adapted for use with a mechanical leer loader, 65

The leer indicated in the drawings may be such as is described in detail in U. S. Patent No. 1,560,481 granted November 3, 1925, to Hartford-Empire Co. as assignee of Vergil Mulholland, but it is to be understood that the present invention is not limited to that particular type of leer, 70

The receiving end of the leer tunnel is indicated at 11. An opening 12 to the leer tunnel is controlled by means of a vertically adjustable door or gate 13 which varies the opening 12 to accommodate glassware of different heights. A conveyor 14 traveling in the direction indicated by the arrow A carries the glassware which is being annealed, 75

As shown in Figs. 1 and 2, the wind-box 15 is mounted outside of the tunnel 11 and slightly in advance of the opening 12. As indicated at 16, the lower part of the rear wall of the wind-box 15 is curved forwardly to provide an orifice 17 which preferably extends the entire width of the leer tunnel. The wind-box 15 is supported in the ways or guides 18 and may be adjusted to various positions therein. The wind-box 15 is then held in adjusted position by the pins 19, one at each edge of the wind-box. Each pin passes through one of a series of holes in a guide 18 and engages a hole 20, one of the latter named holes being provided in each side of the wind-box. Air is supplied through the conduit 21 from a suitable source, not shown. The end of this conduit has a cross section which is thin or flat so that the end of the conduit may slide read- 90

ily through the opening 23 in the wind-box 15. This slidable connection between the end 22 of the conduit and the wind-box permits adjustment of the wind-box in the guides 18 without any change in the position of the conduit.

In operation, a constant current of air moving in the direction indicated by the arrows B prevents the air immediately in front of the leer from becoming greatly heated. The passage of the air through the wind-box also serves to keep its temperature down and makes it more effective as a heat barrier for the radiated heat.

Another and the more important result of this arrangement is the shielding from the leer tunnel of drafts of air tending to blow into the hot end of the leer. The ideal condition is to have neither indrafts nor outdrafts, but to have the air motionless in the leer tunnel. From a practical standpoint this is impossible and, as it is at the hot end of the leer that the glass is most sensitive to thermal changes, the usual practice is to have a slight current of air from the cool end of the leer tunnel toward the hot end and therefore a slight outdraft of air at the receiving end. Decided drafts externally of the leer may at times over-come this slight outdraft and force cool air into the tunnel with very detrimental results. The blast of air provided by this arrangement serves to counteract these external drafts which are irregular in their nature and occurrence.

In some of the more modern plants, the glassware is placed on the conveyor by an automatic stacker, thus dispensing with the services of the carrying-in boy. In such cases, the use of the wind-box 15 as a radiation shield is no longer necessary. Fig. 3 shows a modified arrangement for such a leer. The wind-box 15, being no longer used as a radiation shield, and sometimes being in the way of the mechanism of the automatic stacker, is fastened directly to the door or gate 13 and moves with the gate when the latter is adjusted in position.

Flexible means, as a hose 24, may be used to connect the wind-box with a suitable source of air supply. In this modification, the only purpose is to counteract the tendency of the external air to set up indrafts of air. The blast of air discharging from the orifice 17 is downward and across the opening 12 but should not blow directly on the ware as it passes along on the conveyor although the momentary passage of the ware through the blast of air is not detrimental.

It is to be understood that the different embodiments of the invention described above are for the purpose of illustration only, and various changes may be made therein and other modifications used in place thereof without departing from the spirit

and scope of the invention as defined in the appended claims.

I claim:

1. For a tunnel leer having an opening at the receiving end thereof, a radiation shield adjacent to said opening and outside said tunnel, said shield having an air passage extending therethrough, and means for supplying air to the inlet end of such passage, said passage having an orifice at its outlet end for discharging the air across and away from said opening.

2. Apparatus for annealing glassware, comprising a tunnel having the ends thereof open to the outer atmosphere, one end being for the reception of the glassware and having an adjustable door for controlling the height of the opening to the tunnel, a wind-box attached to said door and adjustable therewith, said wind-box having a discharge orifice directed across the entrance to said tunnel.

3. Apparatus for annealing glassware, comprising a tunnel having the ends thereof open to the outer atmosphere, one end being for the reception of the glassware and having an adjustable door for controlling the height of the opening to the tunnel, a wind-box attached to said door and adjustable therewith, said wind-box extending the width of said opening and having a discharge orifice directed across the entrance to said tunnel.

4. The combination with a tunnel leer having an opening at the receiving end thereof, of a radiation shield adjacent to said opening and outside said tunnel, said shield having an air passage extending therethrough, means for supplying air to the inlet end of such passage, said passage having an orifice at its outlet end for discharging the air away from said opening, and means for adjustably varying the vertical distance between said orifice and the floor of said tunnel when annealing glass articles of varying heights.

Signed at Elmira, N. Y., this 26th day of March, 1928.

CLAUDE NAGLE.
